(57) **CLAIM**

The ornamental design for a six-pronged fork, as shown and described.

DESCRIPTION

FIG. 1 is a top front perspective view of a six-pronged fork, showing my new design;

FIG. 2 is a top plan view thereof;

FIG. 3 is a bottom plan view thereof;

FIG. 4 is a front elevation view thereof, with the rear elevation view being a mirror image thereof;

FIG. 5 is a left side elevation view thereof; and,

FIG. 6 is a right side elevation view thereof.

The broken lines shown in the drawings depict a portion of the article that forms no part of the claimed design.

1 Claim, 3 Drawing Sheets
